(57) **CLAIM**

The ornamental design for a toy robot, as shown and described.

DESCRIPTION

FIG. 1 is a top, front, right perspective view of a toy robot showing the new design;

FIG. 2 is a top, front, left perspective view thereof;

FIG. 3 is a top, rear, left perspective view thereof;

FIG. 4 is a top, rear, right perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The dashed lines shown in the drawings illustrate portions of the toy robot that form no part of the claimed design.
